UNITED STATES PATENT OFFICE

118,043

DESIGN FOR A COMBINED ASHTRAY AND
RECEPTACLE

Montgomery Hare, St. James, N. Y.

Application June 28, 1939, Serial No. 85,741

Term of patent 3½ years

To all whom it may concern:

Be it known that I, Montgomery Hare, a citizen of the United States, residing at St. James, in the county of Suffolk and State of New York, have invented a new, original, and ornamental Design for a Combined Ashtray and Receptacle, of which the following is a specification, reference being had to the accompanying drawing, forming part thereof.

In the drawing

Fig. 1 is a perspective view of a combined ashtray and receptacle showing my new design.

Fig. 2 shows a plan view of the combined ashtray and receptacle, and

Fig. 3 is a cross-section along line 3—3 of the ashtray forming a part of the complete design shown in Fig. 1.

I claim:

The ornamental design for a combined ashtray and receptacle, substantially as shown.

MONTGOMERY HARE.
